UNITED STATES PATENT OFFICE.

WILLIAM DUDLEY ROY, OF NASHVILLE, TENNESSEE.

DECK OF CARDS.

1,355,782.

Specification of Letters Patent. Patented Oct. 12, 1920.

Application filed April 19, 1919. Serial No. 291,227.

To all whom it may concern:

Be it known that I, WILLIAM DUDLEY ROY, a citizen of the United States, residing at Nashville, in the county of Davidson and State of Tennessee, have invented certain new and useful Improvements in Deck of Cards; and I do hereby declare the following to be a full, clear, and exact description of the invention, such as will enable others skilled in the art to which it appertains to make and use the same.

The present invention relates to a deck of cards for playing a game called "Rescue," and it is the object of the invention to provide a deck of cards provided with a novel arrangement of military insignia, representations and value marks, including "Rescue" cards representing the Red Cross service, officer cards of different ranks and service, and game cards of different numerical values and representing different services, whereby the cards provide for the playing of an interesting and patriotic game.

With the foregoing and other objects in view, which will be apparent as the invention is better understood, the invention resides in the representation on the cards of various branches of the service and official rank, with other markings, as hereinafter described and claimed, it being understood that slight changes or variations can be made within the scope of what is claimed without departing from the spirit of the invention.

The invention is illustrated in the accompanying drawings, wherein—

Fig. 2 is a view of the "General" cards.

Fig. 3 is a view of the "Colonel" cards.

Fig. 4 is a view of the "Major" cards.

Fig. 5 is a view of the "Captain" cards.

Fig. 6 is a view of the "Lieutenant" cards which serve as combination officer and game cards.

Fig. 7 illustrates the game cards representing the aviation service.

Fig. 8 is a view of the game cards representing the artillery service.

Fig. 9 is a view of the game cards representing the cavalry service.

Fig. 10 is a view of the game cards representing the infantry service.

The deck includes four "Rescue" or "Nurse" cards 1 having printed or otherwise provided thereon the pictures or representations 2 of Red Cross nurses, with the title "Rescue" as indicated at 3. These cards are of supreme power in playing the game, and have no service distinction, being always in service and taking other cards regardless of whether or not they are in the service called.

There are five sets of "Officer" cards representing official ranks of different grades from lieutenant to general. The "General" cards 4 of which there are four cards, bear 65 the insignia 5 of a general including the stars which are illustrated, and said cards have the title "General" printed or otherwise provided thereon. There are four of each of the "Officer" cards, and the "Colonel" cards 70 7 have the insignia 8 thereon of a colonel, including the eagle, and also bears the title of "Colonel" as at 9. The "Major" cards 10 bear the leaf insignia 11 of a major, and the title "Major," as at 12, and the "Captain" 75 cards 13 bear the double bar insignia 14 of a captain, and the title "Captain" as at 15, while the "Lieutenant" cards 16 bear the single bar insignia 17 of a lieutenant, with the title "Lieutenant" as at 18. These 80 "Officer" cards rank in value according to the military rank represented, the lieutenant being the lowest rank and the general the highest.

There are four services represented, and 85 one card of each of the five sets of "Officer" cards have printed or otherwise provided thereon near certain corners the picture or representation 19 of an aeroplane, representing the aerial service, and another card of 90 each set has the picture or representation 20 of a cannon, standing for the artillery service next in rank to the aerial service, the aerial service being given the highest rank. The third card of each set of "Officer" cards 95 has the picture or representation 21 of a cavalryman representing the cavalry service which is third in rank, while the fourth card of each set has the picture or representation 22 of an infantryman representing 100 the infantry service which is of lowest rank. Thus, the "Officer" cards bear insignia and titles representing official rank of increasing military order and representative numerical value, and said cards also 105 have representations for the aviation, artillery, cavalry and infantry services, in order that the "Officer" cards of each set graduate in value according to service, and the cards of the several sets graduate in value according to official rank represented.

The "Lieutenant" cards 16 are combination "Officer" and game cards, they being provided in addition to the service representations, the numerals 10 as shown at 23, giving these cards a numerical value in the game, in addition to the official rank.

10 The game cards 24, 25, 26 and 27 of which there are four suits are provided respectively with the pictures or representations of an aeroplane 28, cannon 29, cavalrymen 30 and infantrymen 31, representing the 15 aviation, artillery, cavalry and infantry services, and each set of these cards have the numerals, as indicated at 32, running from 2 to 9, so that the game cards of each set are of different numerical values.

20 In playing this game, the players cut the cards for deal, that player who cuts the highest "Officer" card dealing, and the dealer deals each player six cards from the left to the right. Beginning from the player 25 left of the dealer each one will bid as many points as he thinks can be played from his hand, though not less than two points, nor more than the actual number of points they hold in hand that he intends to call service

30 on, although if a player does get more than the number of points he holds in his hand, he is subject to being challenged by either of the other players. For example, if a player holds two "Officer" cards and bids 35 three points, and is awarded the bid and calls for the aviation service, should the next player hold two "Officer" cards in the aviation service and a "Rescue" card, this player has a right to challenge the bidder 40 and the bidder is compelled to show his service cards. If the bidder cannot show three "Officer" cards in the service he calls, he is set back as many points as he bids. The challenger must be able to show three 45 cards in the call service or he is set back the same number of points as the player who calls the service. In every case, the player who calls the service retains his privilege to call service. the highest bidder 50 calling the service. The service that is called by a player who outbids the other players is termed the "Call" service and the call service cards outrank the other service cards. The cards in the call service will 55 take any card of other service regardless of their rank.

The game is played in the usual manner by leading and following, and each player must follow service unless they have a 60 "Rescue" card and wish to take the trick by "Rescuing it" and when playing a "Rescue" card, it is compulsory to use the words "I Rescue" and unless the player does, the service cards in power will outrank the "Rescue" cards. If a player has neither a call 65 service card or a "Rescue" card, he can play any card he desires.

In scoring, anyone of the "Officer" cards counts one point each for the player who catches or holds same at the end of the 70 game, or when the hand is played out, if they are in the call service. Those not in the call service do not count. The "Lieutenant" card is a combination card holding its taking power as an "Officer" 75 card and also counting ten points in the game when in the call service. The "Lieutenant" card out of the call service has only a taking power of cards below it 80 out of the same service. The game consists of ten points. Game counts four points and each "Officer" card in the service counts one point, and each "Rescue" card counts one point. Game cards only count when in the call service, and each game card when in 85 the call service counts as many for game as the numerals thereon represent. The player having the greatest numerical count in game cards in the call service is entitled to 90 the four points for game.

90 Other games can also be played with the deck as will suggest themselves to the players.

Having thus described the invention, what is claimed as new is:—

95 A deck of cards for playing a game of "Rescue" including game, "Officer" and "Rescue" cards, the game cards having service illustrations thereon of aeroplanes, cannons, cavalry, and infantry distinguishing 100 said cards from one another by different services and the cards of each service having value numerals thereon graduated in value, the "Officer" cards bearing the insignia of 105 lieutenant, captain, major, colonel and general, there being four "Officer" cards of each grade and same having service illustrations thereon corresponding to the game cards to distinguish the "Officer" cards of each 110 grade from one another by different services, the "Officer" cards which bear the insignia of lieutenant also having value numerals thereon of greater value than those of the 115 game cards to be used as combination game and "Officer" cards, and the "Rescue" cards 120 having illustrations thereon of a Red Cross nurse and being of higher value than the game and "Officer" cards to "Rescue" any of the other cards during the playing of the game as described.

120 In testimony whereof I have signed my name to this specification in the presence of two subscribing witnesses.
